UNITED STATES PATENT OFFICE

2,683,542

SELF-CLEANING HIGH LIFT BUCKET

Alfred Baker, Washington, Pa.

Continuation of applications Serial No. 212,901, February 27, 1951, and Serial No. 275,989, March 11, 1952. This application December 30, 1952, Serial No. 328,769

9 Claims. (Cl. 214—140)

1

This invention relates generally to excavating machines and more particularly to improvements in the high lift excavator.

This application is a continuation of my application Serial No. 212,901 filed February 27, 1951, and 275,989, filed March 11, 1952, both now abandoned. The disclosures of these previously filed applications have been combined with no new matter to form the disclosure of this application.

When excavating a gummy clay commonly called gumbo, it is very difficult, if not impossible, to clean the high lift bucket of the clay when digging and loading vehicles. It is substantially impossible to work continuously as the operator is required to leave his control position in the high lift and use a shovel or crowbar or other suitable means for digging out the high lift bucket in order to permit him to dig with some efficiency, otherwise the partly filled high lift bucket will not permit him to dig and load the trucks as readily as he could in dry dirt or shale.

The object of this invention is the provision of a scraper arm for use at the high lift bucket for the purpose of scraping the bucket as it is tipped to empty the same.

Another object of this invention is the provision of means for automatically or selectively permitting the scraper arm to remain inoperative. When handling, digging stone or heavy shale it is best not to move the scraper arm as the boulders or other heavy rock will fall of their own accord and the bucket does not need to be scraped at this time. If the scraper arm is forced to operate when stone is in the high lift bucket, the weight of the stone is apt to break the chain or other member of the scraper device. This improvement is also directed to an interlocking means for placing a scraper arm in or out of service at the selection of the operator.

Another object of this invention is the provision of means for automatically operating the scraper arm. The scraper arm is biased to scrape the bucket when dumped, and if the load is too heavy, it will not move. When handling or digging stone or heavy shale, the scraper arm pushes against such boulders or other heavy rock, and if their weight is too great, the arm will not move.

Another object of this invention is the provision for automatically scraping a high lift bucket while dumping the same.

Another object is the provision of a pressure biased scraping blade for the bucket of an earth moving device which operates to scrape the material out of a tilting bucket unless the weight of the material is greater than a predetermined amount. The ultimate pressure to resist operation of the scraper blade may be determined by the size and strength of a spring. If the bucket is handling clay, the spring is usually made suffi-

2

ciently strong to overcome the scraping resistance. If the bucket has a heavy rock or stone it is usually not necessary to scrape the bucket while dumping and the spring does not have sufficient force to shove under the stone and as the bucket tilts, the spring merely stretches further until the stone falls out and the blade then moves around the bucket without encountering resistance.

10 One or more springs may be employed, but the preferred structure employs two springs, one connected to each dumping arm at each side of the bucket. The other ends of the springs are connected to scraper actuating levers that are

15 geared to the scraper blade so that if the bucket is tilted and the scraper blade is against a heavy object so that it cannot move relative to the bucket, then the lever does not move and the springs are expanded. Thus, if the resistance to movement of the scraper blade is relatively small, then the lever stretches the springs only that amount necessary to hold the blade against this resistance while the bucket is tilted, thus causing the latter to be scraped.

20 25 The sprockets and chains may be replaced by levers or crank arms connected together by pitmen. However, the chain connection provides the safety link in the system and will break due to excessive working pressures, thus preventing the more expensive parts from being destroyed.

When the bucket is tilted back to its normal or loading position, the levers are provided with stops that strike the tilting arms and the scraper blade returns to the top of the bucket and the pressure is released from the springs.

30 35 The term crank means is employed herein to define the structure of the sprockets and their connecting chains which may be replaced by gears or crank arms connected by chains or cables.

40 45 Other objects and advantages appear herein-after in the following description and claims.

The accompanying drawings show, for the purpose of exemplification without limiting the invention or the claims thereto, certain practical embodiments of the invention wherein:

Fig. 1 is a side elevation of a high lift indicating the several positions of the bucket.

Fig. 2 is the top plan view of the bucket as shown in Fig. 1.

Fig. 3 is a detailed side elevation of the high lift bucket with a chain plate removed to show the operating chain of the scraper arm.

Fig. 4 is a sectional view taken on the line 4—4 of Fig. 2 showing the high lift bucket with its attachment to the dumping arms.

Fig. 5 is a sectional view taken along the line 5—5 of Fig. 2.

Fig. 6 is a sectional view taken along the line 6—6 of either Fig. 2 or Fig. 4.

60

Fig. 7 is a sectional view of a modification showing a resilient latch.

Fig. 8 is a sectional view of the modification similar to that of Fig. 6.

Fig. 9 is a detailed view of the resilient latch and lever.

The high lift excavating machine as illustrated on the drawings comprises the mobile power unit or tractor 1 which has pivoted thereto a pair of lifting arms 2 and a pair of dumping arms 3. The lifting arms 2 are pivoted at 4 to the frame on the tractor and are actuated by the pivotally mounted fluid-operated cylinders 5 which extend and retract their pistons 6 that are pivoted at their outer ends 7 to the plates 8 on the underside of the lifting arms 2. As shown in Fig. 1 the lifting arms 2 supporting the bucket 10 are illustrated in their extreme positions, the lower position being a position when the bucket 10 is resting on the ground and the upper position being the uppermost height that the bucket can be raised as indicated in dotted lines.

The dumping arms 3 are pivoted at 11 to the end of the plates 12, the opposite ends of which are pivoted on the pins 4 which is the same pivot center that supports the lifting arms. As noted the dumping arms 3 each has a knee 13 which permits the operation thereof by swinging the plates 12. The plates 12 are actuated by the pivotally mounted cylinders 14, each of which has a piston 15 pivotally secured to its respective plate 12 as indicated at 16. The dumping arms 3 may assume the same position with respect to the lifting arms 2 when the bucket 10 is on the ground or when the bucket 10 is in the air and as illustrated at 17. However when the cylinders 14 are energized to move the plates 12 and their dumping arms 3 outwardly, the bucket 10 is in the position as indicated in dot and dash lines at 18.

The bucket 10 is pivoted at 20 to the ends of the lifting arms. The pivots 20 are carried by the dual pair of plates 21 on the underside of the bucket. Two other pairs of ears or plates are provided at 22 for receiving the shafts 23 which pivotally secure the dumping arms 3 relative to the bucket 10 as shown in Figs. 4 and 6. The shafts 23 may be made into one single long shaft but the short stub shafts work satisfactorily.

Each of the shafts 23 is journaled in its respective dumping arm 3 and the plates 22, and also in the bearings 24 in rearwardly projecting housings 25 on the back of the bucket 10. The outer end of each shaft 23 has a sprocket gear 19 secured thereto and is retained within each housing 25. Shaft 23 is provided with the clutch member 26 which is splined or otherwise keyed to the shaft 23 as indicated at 21. The clutch member 26 has a plate 28 welded thereto, which plate is provided with an outwardly open slot 29 as shown in Fig. 4 arranged to receive the locking latch or detent 30 which is pivotally secured to the dumping arm as indicated at 31 in Fig. 2. A servomotor 32 is fastened on the dumping arm 3 and is provided with a piston 33 which is pivotally attached to the latch 30 for the purpose of inserting and retracting the same in the slot 29. The servomotor 32 may be a fluid-operated cylinder or a solenoid or it may be actuated manually. Nevertheless the servomotor is preferably controlled from the operator's seat in the vehicle or tractor 1. When the piston 33 is retracted the latch 30 is withdrawn from the slot 29 in the plate 28 and, since the shaft 23 idles in the

bearings 24 and the plates 22 and the dumping arm 3, the shaft is free to rotate relative to these members when the latch 30 is withdrawn. However, when the latch 30 is inserted in the slot 29, the shaft 23 becomes locked relative to the dumping arm 3.

As shown in Fig. 3 the outer end of each of the shafts 23 has the sprocket gear 19 secured thereto. The high lift bucket 10 is provided with an arcuate rear wall, as indicated at 35, so that it may have the scraper blade 36 with its beveled cutting edges 37 operate from the upper position, as indicated in Fig. 4, to the lower position as indicated at 18 in Fig. 1. The scraper blade 36 is secured to the ends of the radial arms 38 that are fixedly attached to the stub shafts 40 in the center of the arc 35. The shafts 40 extend through the wall of the bucket 10 and have secured thereto the sprocket gear 41 as indicated in Figs. 3 and 5. The sprocket gear 41 has twenty teeth and the gear 19 has thirty teeth. Thus the sprocket gear 41 has two-thirds of the number of teeth as the sprocket gear 19 and since they are connected by the chain 42, the sprocket gear 41 will be rotated with its shaft 40 when the bucket 10 is moved relative to the pivot point 20 by the dumping arm 3. In view of the fact that the sprocket gear 19 is fixed relatively to the dumping arm, the bucket is revolved about the pivot point 20, the chain 42 in effect passes around the sprocket 19 which provides motion to the small sprocket 41 and causes the scraper blade to travel from the position as indicated at 43 to 44 in Fig. 1, when the bucket 10 is tipped from the position as indicated at 17 to the position as indicated at 18.

When the servomotor 32 is energized to withdraw the latch 30 and unlock the plate 28 relative to the dumping arm 3, the scraper blade 36 will remain at the top of the bucket, as illustrated in Fig. 4, as its friction will not permit it to move in any way even though the bucket is manipulated for the full extent. The plate 28 and the shaft 23 will remain in the same relative position to the bucket 10, as illustrated in Fig. 4, until the dumping arm is brought to the lowermost position, as illustrated in full lines in Fig. 1 and in Fig. 4, so as to permit the latch 30 to be slid back in the slot 29 for locking the shaft 23 relative to the dumping arm 3. Thus by simple manipulation of a control of the servomotor 32 one may invoke the use of the scraper blade 36 for the purpose of scraping the bucket when it is operating in sticky clay and when operating in stones the scraper blade may be released and permitted to stay at the top of the bucket where it will not be harmed.

A guide plate 45 may be placed within the enclosure of the sprocket gears 19 and 41 for the purpose of taking up the slack in the chain and in order to make the walking action of the chain around the sprocket 19 effective in rotating the sprocket gear 41. If it is desirable to remove the chain, the guide 45 may be removed which materially loosens the chain in its flight. A cover 46 is provided to enclose the sprockets 19 and 41 to prevent dirt from entering therein. Thus the chain and sprockets may operate in oil or grease which can seep through the bearings past the shafts 40 and 23 and thereby lubricate the arms 38 within the bucket and also lubricate the bearing 24.

As shown in Fig. 2 the high lifts employ a dual pair of lifting arms and a dual pair of dumping arms and require two spaced pivotal points which

support the bucket 10 on the end of the arms. Only one side of the high lift has been described, however, the opposite side is exactly the same and is operated in unison therewith. It is far better to provide a driving means on both sides of the high lift bucket 10 to dump the same.

In the modification shown in Figs. 7, 8 and 9 illustrating the automatically operated scraper arm, the clutch members 26 are replaced by the right and left hand lever members 47 and 48 which are splined or otherwise keyed to the shafts 23 as indicated at 27. The outer ends of the levers are connected by the rod 49 so that they will operate in unison. A stop 50 in the form of a projection is welded to the side of each of the arms 47 and 48 and is arranged to strike its respective plate 51 welded to the dumping arms 3. As the dumping arms 3 pull the bucket back to the positions shown in Figs. 1 and 7 the stops 50 engage the plates 51 and prevent further pivoting in this direction. The rod 49 has a spring 52 attached at each end thereof adjacent the levers 47 and 48. The other ends of these springs are fastened to a bracket 54 on its respective dumping arm 3. Upon fastening the springs 52 to the rod 49 they are subjected to the greatest movement. Holes 53 are provided in the levers 47 and 48 for shortening the movement of the spring.

The shaft 23 is free to rotate relative to the bucket and the dumping arms 3, but being secured to the levers 47 and 48 is limited in its movement when the stops 50 strike the plates 51.

In view of the fact that the sprocket gear 34 is fixed relatively to the dumping levers 47 and 48, the chain 42 in effect passes around the sprocket 34 which provides motion to the small sprocket 41 and causes the scraper blade to travel from the position as indicated at 43 into 44 in Fig. 1, when the bucket 10 is tipped from the position as indicated at 17 to the position as indicated at 18. The stub shaft 40 is also journaled in the bearing carried by the plate 46.

When the resistance to movement of the scraper blade is greater than the tension on the springs 52, the levers move with the bucket and the springs expand. The scraper blade 36 will remain against the obstruction in the bucket until this resistance to movement is removed, then the stretched springs retract the levers 47 and 48 to swing the scraper through its arc. Thus, the scraper blade 36 functions automatically for the purpose of scraping the bucket when it is operating in sticky clay, and when operating in stones the resistance to movement of the scraper blade may even keep it at the top of the bucket until the resistance is removed.

I claim:

1. A high lift excavator comprising, a mobile power unit, lift arm means operatively carried by said power unit and pivotally attached to a bucket to raise the same, a dump arm means operatively carried by said power unit and pivotally attached to said bucket in spaced relation to the pivotal attachment of the lift arm means to tilt said bucket forwardly on the pivot of the lift arm means to empty the same, a pivoted member on said bucket and having a dirt scraper attached thereto, and intermediate drive means connecting said pivoted member to the dump arm means to multiply the rotation of the scraper making it travel through a greater arc than the rotation of the bucket as the latter is tipped forwardly by the dump arm means to empty the same.

2. The structure of claim 1 characterized in that said bucket has a circular arcuate portion and said scraper comprises a U-shaped member having its ends journaled on each side of said bucket to scrape the circular arcuate portion.

3. The structure of claim 1 characterized in that said pivoted member is a sprocket and the intermediate drive means includes a sprocket chain and a second sprocket with a connecting means 10 to hold the second sprocket relative to the dump arm means and produce relative movement between the bucket and the scraper when the bucket is dumped.

4. The structure of claim 1 characterized in 15 that said pivoted member and said last-mentioned intermediate drive means include sprockets which are connected by a chain to multiply the rotary action of the scraper.

5. The structure of claim 4 characterized in 20 that one of said sprockets is releasably connected to the dump arm means and is journaled on the dumping arm pivot and is selectively locked relative to said dump arm means and when unlocked permits the scraper to remain at rest relative to 25 the bucket when the bucket is tipped.

6. The structure of claim 4 characterized in 30 that one of said sprockets is journaled on the dumping arm pivot and is connected through a resilient means to said dump arm means to permit the scraper to remain at rest relative to the bucket when the resistance to movement of the blade is greater than the flexure of the resilient means when the bucket is tipped.

7. The structure of claim 1 characterized in 35 that said intermediate drive means includes a sprocket attached to said pivoted member, a chain around said sprocket, and resilient means connecting said sprocket and said dump arm means to rotate the scraper and scrape the bucket as the 40 dumping arm means tips the bucket forwardly on the pivot of the lift arm means to dump the same.

8. A high lift excavator comprising, a mobile power unit, lift arm means operatively carried 45 by said power unit and pivotally attached to a bucket to raise the same, a dump arm means operatively carried by said power unit and pivotally attached to said bucket in spaced relation to the pivotal attachment of the lift arm means to tilt

50 said bucket forwardly on the pivot of the lift arm means to empty the same, a pivoted member on said bucket and having a dirt scraper attached thereto, crank means attached to said pivoted member, and intermediate rotary drive means 55 connected through the pivot between the bucket and said dump arm means to drive said crank means and multiply the rotation of the scraper making it travel through a greater arc than the rotation of the bucket to scrape the bucket as the 60 dumping arm means tips the bucket forwardly on the pivot of the lift arm means to dump the same.

9. The structure of claim 8 characterized in 65 that said intermediate rotary drive means is releasably locked relative to said dumping arm means.
